(57) **CLAIM**

The ornamental design of an electronic torque wrench, substantially as shown and described.

DESCRIPTION

FIG. 1 is a perspective view of an electronic torque wrench embodying the design of the present invention;

FIG. 2 is a bottom elevation view of the electronic torque wrench illustrated in FIG. 1;

FIG. 3 is a top elevation view of the electronic torque wrench shown in FIG. 1;

FIG. 4 is a left side view of the electronic torque wrench shown in FIG. 1; and,

FIG. 5 is a right side view of the electronic torque wrench shown in FIG. 1.
